United States Patent Office.

WILLIAM NELSON, OF ANDERSON, INDIANA.

Design No. 4,692, dated February 28, 1871.

DESIGN FOR WINDOW-FASTENERS.

The Schedule referred to in these Letters Patent and making part of the same.

To all whom it may concern:

Be it known that I, WILLIAM NELSON, of Anderson, in the county of Madison and State of Indiana, have invented a certain new and useful Design for a Window-Fastener; and I do hereby declare that the following is a full, clear, and exact description thereof, reference being had to the accompanying drawing and to the letters of reference marked thereon which form a part of this specification, in which is represented a plan of the fastener.

To enable others skilled in the art to make and use my invention, I will now describe its construction and operation.

A represents the body of the fastener, which is excavated, as shown in the drawing, and provided with the inclined slot b, through which a screw passes, and thus secures the fastener to the sash.

a represents a weighted arm, cast upon the lower

extremity of body A, and e, a hook upon its opposite side.

As the accompanying drawing fully represents the design for which I desire Letters Patent, it is useless to further describe it. Suffice it to say that the weighted arm will aid much in the effective working of the fastener, as it will cause the hook to swing into the notches cut in the casing.

What I claim is—

The design herein shown and described for a window-sash fastener.

In testimony that I claim the foregoing as my own I affix my signature in presence of two witnesses.

WILLIAM NELSON.
